(57) CLAIM

The ornamental design for a bathroom toilet contour rug.

DESCRIPTION

FIG. 1 is a left perspective view of the rug showing the design as applied to the perimeter (convexed and concaved sculpting of outer edges) of the bathroom rug.

FIG. 2 is a left perspective view of the rug as it relates to a toilet stool; and,

FIG. 3 is a top plan view of the bathroom rug embodying my new invention (design).

The back side of the rug is flat.

The pattern, which is partially shown for ease of illustration, represents a conventional fabric and is understood to repeat uniformly throughout the indicated area.

The broken line showing is for illustrative purposes only and forms no part of the claimed design.
